UNITED STATES PATENT OFFICE

HOWARD D. YODER, OF DETROIT, MICHIGAN, ASSIGNOR TO PENBERTHY INJECTOR COMPANY, OF DETROIT, MICHIGAN, A CORPORATION OF DELAWARE.

PORTABLE SUMP PUMP

Application filed August 22, 1927. Serial No. 214,519.

This invention relates to an improved automatically controlled sump pump which may be installed in the basements of homes, office buildings, and the like, and may be 5 readily moved from place to place to meet the exigencies of the flooding of basements due to seepage, back water, or the bursting of water pipes, and when installed is simple and reliable in operation.

10 An object of this invention is to provide an exceedingly compact sump pumping device to economize floor space by disposing the pump, the strainer, the control float, and the driving motor in vertical alignment.

15 A further object of this invention is to provide a sump pumping device having a vertical tube or shaft casing supported by a spider bracket on a pump so that the casing may serve as a guide for the float and the 20 motor control means operated by the float, and to support the driving motor and house the driving shaft extending between the motor and the pump.

An important object of this invention is 25 to provide in a sump pumping device of the class described means whereby the driving shaft enters the pump casing through the suction side of the pump without requiring a packed joint between the shaft and the 30 pump.

Other and further important objects of this invention will be apparent from the disclosures in the specification and the accompanying drawing.

35 This invention (in a preferred form) is illustrated in the drawing and hereinafter more fully described.

On the drawing:

40 Figure 1 is a side elevation of the assembled pump.

Figure 2 is a fragmentary section view of the pump of Figure 1, looking from the left, and with parts in elevation.

As shown on the drawing:

45 The reference numeral 10 indicates a sump pump base upon which is detachably mounted a centrifugal sump pump casing 11. Within the casing is an impeller 12 which is driven by a vertical shaft 13 housed in a tube 14. Integral with the pump casing 11 is a

tube supporting member or spider 17 comprising upwardly extending fins carrying an integrally formed annular cup-like ring 18 having a right angled inwardly projecting portion 19 and downwardly depending therefrom a collar member 20 carrying a guiding sleeve bearing 21 in which the shaft 13 is journaled. The inner face of the wall of the ring 18 is threaded to engage with threads on the outer face of the tube 14 while the 60 lower end of the tube bears on an abutment formed by the projection 19. A set screw 22 locks the tube in place in the ring 18.

A strainer 16 is detachably secured on top of the pump casing 11 and forms a housing 65 protecting the tube supporting means 17.

The upper wall of the pump casing 11 has a central opening through which the shaft 13 projects and through which the liquid to be pumped passes to the impeller 22 for discharge through the outlet 39 and its connections.

It is important to note that because the shaft 13 is housed in the tube 14 seated in the tube support 17 and is guided through the 75 sleeve 21 therein it passes through the suction opening of the pump without requiring a packed joint.

The tube 14 guides a metal float 23 and the float alternately engages with float travel 80 limit stops 24 and 25. The limit stops consist of rings 24 and 25 fitting loosely around the tube 14 and having suitable means for detachably connecting them with a switch operating rod 26. The switch operating rod 85 engages a switch lever 27 of a switch 28 mounted on a casing 36 to control a motor 29.

The upper portion of the tube 14 threadedly engages a sleeve coupling 30 and abuts an inwardly projecting annular shoulder 31 near the lower end of the coupling 30. A set screw 32 locks the tube in the coupling 30. An apertured partition 33 on the upper end of the coupling carries a guiding sleeve 34 in which 95 the shaft 13 is journaled.

The shaft 13 and its attached impeller 12 is held suspended by suitable bearing means 35 housed in the casing 36 as shown. The casing 36 threadedly engages with the upper 100

end of the sleeve coupling 30 and the set screw 37 locks it in position.

The motor 29 is suitably mounted on the upper end of the casing 36 and the motor shaft is coupled to the pump shaft 13 by means of a flexible coupling 38 housed within the casing.

The stop rings 24 and 25 are adjustable along the tube 14. The float 23, when the pump is inserted in a sump or like place for pumping purposes, and the stops 24 and 25 are adjusted to the height of the water to be pumped. The float 23 will be moved upwardly against the upper stop 25, thereby actuating the switch 28 to operate the motor. The motor will continue until the float 23 drops, engaging the lower stop 24, whereupon the switch is actuated to stop the motor.

The device is a portable sump pump and may be readily carried from place to place. The outlet 39 has connected to it hose or other connections for delivering the fluid pumped to any place of disposal.

The strainer 16 prevents the entry into the pump casing of dirt and the like, thus permitting an operation of the pump under usual conditions of service.

I am aware that many changes may be made, and numerous details of construction may be varied through a wide range without departing from the principles of this invention, and I therefore do not purpose limiting the patent granted hereon, otherwise than necessitated by the prior art.

35 I claim as my invention:

1. A portable electric sump pump comprising a base, a centrifugal pump casing on said base, an impeller in said pump casing, a spider on said pump casing terminating in a cup, a shaft tube extending upwardly from the cup, a motor on the upper end of said tube, and a shaft within said tube carrying said impeller, said shaft being mainly supported by bearings adjacent the upper end of said tube, a float guided on said tube, and a motor switch arranged to be actuated by said float.

2. A portable electric sump pump comprising a base, a cylindrical pump casing on the base, a spider integral with said pump casing and extending above the same and terminating in a cup, a shaft tube supported in said cup, a casing on the upper end of said tube, a motor support on said last mentioned casing, a shaft connected to the motor passing through said tube and carrying an impeller at its lower end in said pump casing, a bearing in the casing at the upper end of said tube for suspending said shaft in said tube, a strainer above the pump casing and about said spider, and automatic means for controlling said motor responsive to the depth of fluid about said pump.

3. A portable electric sump pump comprising a base, a cylindrical pump casing on the base, a spider integral with said pump

casing and extending above the same and terminating in a cup, a shaft tube supported in said cup, a casing on the upper end of said tube, a motor support on said last mentioned casing, a shaft connected to the motor passing through said tube and carrying an impeller at its lower end in said pump casing, a bearing in the casing at the upper end of said tube for suspending said shaft in said tube, a strainer above the pump casing and about said spider, a float guided on said tube, and adjustable connections responsive to movement of said float for controlling the motor.

4. A portable electric sump pump comprising a base, a cylindrical pump casing on the base, a spider integral with said pump casing and extending above the same and terminating in a cup, a shaft tube supported in said cup, a casing on the upper end of said tube, a motor support on said last mentioned casing, a shaft connected to the motor passing through said tube and carrying an impeller at its lower end in said pump casing, a bearing in the casing at the upper end of said tube for suspending said shaft in said tube, a strainer above the pump casing and about said spider, a guide for the lower end of said shaft included in said spider, the upper wall of said pump casing having an opening through which said guide passes and through which liquid is delivered to the pump casing.

5. A portable sump pump comprising driving means, a base, a centrifugal pump casing on said base having a top inlet, an impeller in said pump casing, a cup shaped support on the casing having a reduced tubular portion depending through the casing inlet, a vertical tube carried by said support, a shaft rotated in said tube and connecting said driving means to said impeller, said shaft extending through and guided within the said tubular portion of said support, and control means for the driving means associated with and guided by said tube.

In testimony whereof I have hereunto subscribed my name at Detroit, Wayne County, Michigan.

HOWARD D. YODER.
